UNITED STATES PATENT OFFICE

ALBERT C. CRANDALL, OF BRAINTREE, MASSACHUSETTS

EXTENSION BOOM FOR DERRICKS

Application filed February 7, 1929. Serial No. 338,101.

My present invention relates to extensible booms, and more particularly to an extension boom for use in hoisting cargoes to and from vessels.

5 Heretofore, in the loading and unloading of ships in port, much valuable time has been wasted due to the fact that with the derricks and booms now in use for such purposes, cargo handlers are unable to work full time 10 on account of the tides. The booms now in use are one piece and after the tide has ebbed for a certain period the boom will not reach to handle the cargo, therefore, it is necessary to stop work and wait for the tide, which not 15 only means a loss of time but also a resulting expense for everyone connected with the ship.

My present boom is designed to meet such shortcomings of the present equipment by being capable of extension and at the same time 20 making possible the reaching of ordinarily inaccessible places by swiveling on itself, heretofore impossible with any solid piece boom.

The principal object therefore, is an extensible derrick boom.

Another object is an extensible boom capable of being swivelled around on itself at approximately 90 degrees.

Other objects and novel features comprising the construction and operation of my invention will appear as the description of the apparatus progresses.

In the drawings illustrating the preferred embodiment of my invention,

35 Fig. 1 shows a side elevation with the boom extended;

Fig. 2 is a section taken on the line 2—2 of Fig. 1;

40 Fig. 3 is a section taken on the line 3—3 of Fig. 1; and

Fig. 4 is a section taken on the line 4—4 of Fig. 2.

In the drawings illustrating my preferred embodiment of the device, 10 indicates a mast, 45 the lower end of which is provided with a swivel member 11 shrunk about a groove provided around the mast 10, the said swivel member 11 being a part of the fixture to which the pulley 12 is attached by means of an offset yoke member 13. The swivel 11 and yoke

member 13 are pivoted at 14 to the lower portion of the boom 15, such that the boom 15 may be raised or lowered on the pivot 14 or the entire boom 15 swivelled about the mast 10 by means of the swivel 11.

At the outer end of the boom 15 there is attached the extensible boom member 16 being provided at its outer end with a collar 17 rigidly attached thereto, and having pivoted thereon at 18 a supporting link member 19 adapted to receive a pulley 20 pivoted therein at 21, a link 22 is also pivoted at 18 and adapted to receive therein a pulley 23 the purpose of which is to provide means for attaching suitable block and tackle to raise and lower cargo.

The pulley 20 is associated with another pulley located on the mast 10 and attached thereto by means of the strap member 25, being pivoted to such mast 10 at 26, and by means of cables 27 associated with pulleys 24 and 20, the outer end of the extensible boom member 16 is thereby provided with raising and lowering means as well as a supporting means when cargo is being handled on the pulley 23. A secondary support means is located at the rear end of the extensible boom member 16 in the form of a suitable eye-bolt 28 associated with a pulley 29 also attached to the top of the mast 10 and a cable 30 is provided therefor.

At 31, there is provided a slidably mounted shackle, comprising an annular ring 32 provided with slots 33 in which slides a spline 34 attached to either side of the boom member 15. The upper portion of the shackle 31 is composed of a bridge member 35 provided at its top center with bearing 36 in which is journalled a forked pin member 37, the lower end of which is threaded at 38 to receive a lock nut 39, which is held thereto by means of a transverse through pin 40. The nut 39 bears up against a thrust washer 41 which is adapted to bear against the under side of the bearing 36. The extreme lower end of the member 37 is rounded at 42 and seated in a cup shaped bearing 43 found in the upper side of the band portion 32.

The rear end of the extensible boom member 16 is flattened off at 44 and adapted to fit

between the two sides 45 of the forked member 37, and a pivot member 46 is adapted to pass through the side members 45 and boom end 44 and be held in place thereto by means of a nut 47.

5 A second slidable shackle 48 is pinned at 49 to the outer end of the boom member 15, the lower side of which is provided with an eye-bolt 50, which carries a link 51 in which is 10 pivoted a pulley 52 for use in raising or lowering cargo. The shackle 48 is welded together at 53 and the two ends 54 and 55 are turned over to form a part of a hinge through which pins 56 pass and engage with similar 15 hinge members 57 and 58, located on the bottom ends of two encircling members 57^a and 58^a adapted to encircle the extensible boom member 16 and slide thereon. Abutting members 59 and 60 are located on the upper 20 ends of the encircling members 58^a and 57^a such that the member 59 passes between the members 60 located on member 57^a and an elongated hole 61 is provided in both the central member 59 and the two members 60, such 25 that a pin 62 may be inserted to hold the members 57^a and 58^a in place, as shown in Figs. 1 and 3.

An internal pulley 65 is pivoted at 66 in the boom member 15 over which runs a cable 67 30 the front end of which is attached to the extensible boom member 16 by means of an eye-bolt 68, and the other end of the cable 67 is attached to a link 69 associated with a pulley 70.

35 The rear end of link 69 is attached to a cable 71 which passes around pulley 12 and over pulley 70 and thereby provide means for extending the extensible boom member 16 into the position shown in Fig. 1, and during such 40 movement of member 16 cables 30 and 27 are brought into use to provide the necessary slack. Where the extensible member 16 is slid in on member 15, the cable 71 is given slack and the cables 30 and 27 are taken up.

45 If it is desired to reach some ordinarily inaccessible point the shackle pin 62 may be removed, dropping the band members 57^a and 58^a as indicated in dotted lines in Fig. 3 and the boom member 16 turned around at 50 an angle with boom 16 by means of the swivel yoke member 37 pivoting in the cup 42 on the boom member 15. The boom member 15 may be maintained at an angle with the boom member 15 by suitable guy cable 80 attached to the member 16, as is customary in everyday practice with ordinary cargo booms.

Having thus described my invention, what I claim as new, is:

55 1. In a hoisting derrick, including a mast, an extensible boom comprising two main parts, the lower part being rotatably and vertically movable about said mast and provided with longitudinally disposed splines attached to either side thereof, a shackle fixed to the outer end of said boom and

adapted to slidably encircle the extension boom located above it, said shackle adapted to be removed from said extension boom, a rear shackle member adapted to be attached to the rear end of said extension boom and pivotally attached thereto, said rear shackle being slidably mounted on said first boom and adapted to cooperate with said splines therein, means for swivelling said extension boom on said first boom and means for sliding said extension boom on said first boom, substantially as shown and described. 70

2. In an extension boom comprising a longitudinally movable member and a longitudinally fixed member, a shackle removably and slidably associated with the extension member of said boom, one side of which is solidly attached to the stationary portion of said boom, a second shackle pivotally attached to the rear end of said movable member in a vertical plane and adapted to slide on said fixed member, said second shackle further adapted to swivel on itself in a substantially horizontal plane, and means for extending said movable member on said fixed member. 85

3. In a hoisting derrick, the combination of a mast, an extensible boom comprising two main parts, the lower part being rotatably and vertically movable about said mast and provided with longitudinally disposed splines attached to either side thereof, a shackle fixed to the outer end of said boom and adapted to slidably encircle the extension boom located above it, said shackle adapted to be removed from said extension boom, a rear shackle member adapted to be attached to the rear end of said extension boom and pivotally attached thereto, said rear shackle being slidably mounted on said first boom and adapted to cooperate with said splines therein, means for swivelling said extension boom on said first boom and means for sliding said extension boom on said first boom, substantially as shown and described. 95 100

4. In an extension boom comprising a longitudinally movable member and a longitudinally fixed member, the combination of a shackle removably and slidably associated with the movable member of said boom, one side of which is solidly attached to the stationary portion of said boom, a second shackle pivotally attached to the rear end of said extensible member in a vertical plane and adapted to slide on said fixed member, said second shackle further adapted to swivel on itself in a substantially horizontal plane, and means for extending said movable member on said fixed member. 110 115

In witness whereof, I hereby subscribe my name this 6th day of January, 1929.

ALBERT C. CRANDALL.
